United States Patent Office

Des. 188,570
Patented Aug. 9, 1960

188,570

PRINTING MACHINE

Joseph J. Ackell, Amityville, N.Y., assignor to Dow Jones & Company, Inc., New York, N.Y., a corporation of Delaware

Filed Feb. 6, 1959, Ser. No. 54,487

Term of patent 14 years

(Cl. D64—11)

FIG. 1

FIG. 2

FIG.3

FIG.4

FIG. 5

Figure 1 is a front elevational view of a printing machine showing my new design;

Figure 2 is a side elevational view thereof as seen from the right of Figure 1;

Figure 3 is a rear elevational view;

Figure 4 is a side elevational view as seen from the left of Figure 1; and

Figure 5 is a top plan view thereof.

Parts of the delivery shelf have been shown broken away in Figures 1, 3 and 5 for convenience of illustration.

I claim:

The ornamental design for a printing machine, as shown and described.
